S. SOLOP,
COMBINED DRILL AND SCREW SET,
APPLICATION FILED DEC. 3, 1921.

1,424,600.

Patented Aug. 1, 1922.

INVENTOR
S. Solop

BY *M. G. Gelin*
ATTORNEY

UNITED STATES PATENT OFFICE.

SYDOR SOLOP, OF BROOKLYN, NEW YORK.

COMBINED DRILL AND SCREW SET.

1,424,600.

Specification of Letters Patent. Patented Aug. 1, 1922.

Application filed December 3, 1921. Serial No. 519,587.

To all whom it may concern:

Be it known that I, SYDOR SOLOP, citizen of Russia, residing at Brooklyn, in the county of Kings and State of New York, 5 have invented certain new and useful Improvements in Combined Drill and Screw Sets, of which the following is a specification.

One of the objects of this invention is to 10 provide an implement generally known as a bit-stock, with means for quickly engaging and disengaging, and at the same time, to positively compel rotation of various gripping means adapted to attachment with the 15 bit-stock spindle.

Another object is the means for manually 20 tightening and releasing the gripping jaws when employed in holding drills, screws and other tools that require rotary motion in 25 their use.

These and other objects are attained by the novel construction and arrangement of parts hereinafter described and shown in the accompanying drawing, forming a material part of this disclosure, and in which:—

Figure 1 is an elevational view of the device as assembled.

Figure 2 is a bottom plan view of the 30 same.

Figure 3 is a partial sectional top plan view taken on the line 3—3 of Figure 1.

Figure 4 is a partial sectional side elevational view of the gripping members.

Figure 5 is a partial sectional bottom plan view taken on line 5—5 of Figure 4.

Referring to the drawings in detail, the numeral 10 designates the offset element of a bit-stock frame having a handle 11 and a 40 lower end or socket 12 provided with forked ears 13 integral therewith.

A thumb actuated latch 14 is engaged between the ears 13 by a pivot 15. A bent flat spring 16, holding the latch in place, 45 is secured to the frame 10 by a screw 17.

Formed in the end of the socket 12, and extending upward therein, is a rectangular opening adapted to receive a square tang 18, as shown in Figure 4.

50 The square tang 18 is an integral part of a screw-threaded spindle 19, the upper end of which is provided with an opening 20 to receive the bolt 21 of the latch.

A star wheel 22, has a tapered hub 23, 55 through which is a screw-threaded opening adapted to adjustably receive the spindle

screw 19. An interiorly threaded connecting link 24, fitted to the spindle is slotted at the ends to receive the jaw members 25, pivoted therein and whose upper, inner portions are in movable engagement with the annular tapered hub 23. The lower, inner ends 26 of the jaw levers are bent inwardly and adapted to center and support various sized screws 27, as shown in Figure 1.

When it is desired to hold a drill 28, or other tools, supplementary jaws 30 are interposed between the regular jaws 25, the inner faces of which are provided with 70 grooves 31 for centering and gripping the drill. The upper ends of the jaws 30 are pivotally connected to a cross member 32, having an integral rectangular projection 33 adapted to enter a similarly shaped recess 75 formed in the lower end of the spindle 19.

Interchangeable with the auxiliary tool holding jaws is a screw driving member 35 having a blade 36 adapted to engage the kerf of a screw as at 27, and a rectangular projection 33, on the upper end, enterable in the recess formed in the end of the spindle screw 19.

As the spindles 19 are readily removable from and interchangeable in the socket 12, 85 any number of individual chucks or gripping heads may be employed for holding different tools, as a starting drill, a body size drill, a countersink and a screw driving bit.

From the drawing it will be seen that by 90 rotating the star wheel about the spindle, the jaws will be opened or closed, thus providing means for quickly placing or removing any article engageable between the jaws.

The cross link 24, being engaged on the 95 screw 19, provides adjustment for the position of the screw driving bit with respect to the diameter of the screw head, a similar adjustment is also required when the auxiliary jaws are employed.

Although the foregoing is descriptive of the preferred embodiment of the invention, it will be apparent that minor changes may be made in its construction, without the exercise of invention or conflicting with the 105 scope of the claims hereto appended.

Having thus described my invention, what I claim as new and desire to secure by Letters Patent, is:—

1. A brace driven tool holder consisting 110 of a spindle exteriorly threaded and having a rectangular projection adapted to fit

a recess formed in the brace, a pair of jaws associated with the spindle, a star wheel for operating the jaws, a pair of auxiliary jaws adjacent the first mentioned jaws, means for 5 rotating the auxiliary jaws consisting of a cross bar pivoted to said auxiliary jaws and having a rectangular projection fitting a recess of similar shape formed in the lower end of the spindle screw, and means for 10 simultaneously closing both pairs of jaws.

2. A brace driven tool holder comprising

a chuck, having inner and outer pairs of pivoted jaws supported by a screw threaded spindle screw, a star wheel for operating and closing the jaws, said jaws having rotary 15 engagement with the spindle, said inner jaws being interchangeably engageable with said spindle, and means for interchangeably connecting said spindle to the brace.

In witness whereof I affix my signature. 20

SYDOR SOLOP.
